VOLTAGE REGULATOR

John F. Walton, McLean, Va., assignor, by mesne assignments, to Halliburton Company, a corporation of Delaware

Filed May 4, 1962, Ser. No. 192,483
16 Claims. (Cl. 323—22)

The present invention relates to voltage regulator circuits and more particularly to shunt and series-connected circuits for regulating the voltage output of negative voltage supplies.

Shunt and series regulator circuits for positive voltage supplies are quite common in the prior art and are extensively employed. With regard to negative voltage supplies series regulator circuits are quite common, the series regulating tube normally being connected in the grounded voltage bus so as to obtain suitable operating potentials. This type of circuit may be readily employed where the negative supply is independent of a positive supply but where a circuit is to supply both positive and negative output voltages relative to ground potential, the connection of the series regulator tube of the negative supply in the ground return lead presents considerable difficulty. More specifically, where a power supply provides both positive and negative voltages and employs a common ground return lead, location of the series regulator tube or tubes of the negative supply in this lead affects the positive voltage supply whenever there is an adjustment in the negative voltage circuit. In order to avoid this interaction of the regulator circuits, additional circuitry must be employed to produce an adjustment in the positive supply whenever an adjustment is made in the negative supply. It has not been possible previously to connect the series regulator tube for the negative supply in the negative voltage lead since, in order to do so, the cathode of the series regulator tube must be connected to the negative output voltage of the rectifier and filter circuit and the anode must be connected to the negative supply output terminal which is normally less negative than the aforesaid voltage. Since the cathode is connected directly to the output from the rectifier circuit, it is connected to the most negative potential subsisting in the circuit and in consequence it is not possible to obtain a suitable bias voltage for the grid of this regulator tube.

It is an object of the present invention to provide a series regulator circuit for a negative voltage supply in which the series regulator tube may be connected in the negative voltage bus.

Difficulty is also experienced in attempting to employ shunt regulator circuits in negative voltage supply systems regardless of whether the negative voltage supply is employed independently or is utilized in conjunction with a positive supply. The reason for this difficulty is that in the normal shunt control circuit, a resistor is connected in series with the negative voltage bus and the current through this resistor is varied by means of shunt connected tubes. The cathodes of the shunt tubes are connected to the negative output terminal or lead and there is no readily available voltage for biasing the grids of the tubes negative with respect to the cathodes. It is undesirable to utilize cathode bias resistors since such resistors must have a relatively high impedance and materially reduce the current that can be drawn through any given shunt regulator tube. In order to provide a circuit having a given percentage of regulation, a larger number

2

of shunt connected tubes must be employed where cathode bias is utilized than if cathode bias is not required.

It is therefore another object of the present invention to provide a shunt regulator circuit for negative supplies in which a suitable bias voltage for the control grid of the shunt regulator tube or tubes may be obtained without resort to the use of cathode bias resistors connected in series with the cathode circuit of the tubes.

In accordance with the present invention, there is provided a voltage regulator circuit in which an error signal indicating deviation of a negative output voltage from a desired value is amplified in an amplifier in which a distinct, small and low capacitance power supply is employed to supply the anode voltage for the output stage of the amplifier. This power supply is connected between the anode and the load resistor of this last stage of amplification. The load resistor is returned to the negative output bus and due to the location of the last stage power supply and the load resistor as set forth above, the junction of the load resistor and the individual power supply is negative relative to the voltage of the negative output bus. In consequence, by appropriately proportioning the values of the voltage of the individual supply, the quiescent current through the last stage of amplification and the value of a load resistor, a suitable bias may be obtained for the control grid of the control tube whether it be a series or shunt connected control tube.

By connecting the junction of this individual power supply and the load resistor directly to the control grids of the regulator tube or tubes, the proper operating potential is developed directly on the control grids and also the signal currents which are developed across this load resistor are directly coupled to the control grids. The circuit therefore is a direct coupled circuit having excellent response to high frequency transients and exhibiting low drift characteristics. The shunt capacity to ground of the individual power supply tends to by-pass the high frequency signal components of the control voltage and therefore it is necessary that the individual power supply have a low shunt capacity to ground. This capacity should be of the order of 20 micro-micro-farads in order to prevent undue loss of signals up to one megacycle per second. A power supply suitable for such a use is disclosed and claimed in U.S. Patent No. 2,914,719 of Walton et al. assigned to the assignee of the present invention.

It is therefore, another object of the present invention to provide a voltage regulator circuit for negative voltage supplies in which a separate power supply is employed as an anode supply for the last stage of an error signal amplification circuit and is further employed as a means for coupling the error signal to a control tube so as to develop a suitable operating bias on the control grid of the voltage control tube or tubes.

It is still another object of the present invention to provide a series connected voltage regulator circuit for negative voltage supplies in which the series regulator tube is connected in the negative voltage bus or lead and in which a distinct voltage source is employed for the last stage of an error signal amplification circuit in order to develop appropriate operating bias on the control grid of the series regulator tube.

Yet another object of the present invention is to provide a shunt-connected regulator circuit for negative voltage supplies in which a distinct power supply is employed for the anode circuit of the last stage of the signal amplification circuit in order to develop an appropriate operating bias on the control grids of the shunt connected

tubes without requiring the use of cathode resistors in conjunction with the regulator tubes.

It is still another object of the present invention to provide a voltage regulator circuit for negative voltage supplies in which a separate power supply is employed to couple an error signal from an error signal amplification circuit to the control grid of a regulator tube so as to provide a proper operating bias on the control grid relative to the cathode of the regulator tube.

The above and still further objects, features and advantages of the present invention will become apparent upon consideration of the following detailed description of several embodiments thereof, especially when taken in conjunction with the accompanying drawings, wherein:

FIGURE 1 is a schematic electrical diagram of the series regulator circuit incorporating the principles of the present invention; and

FIGURE 2 is a schematic electrical diagram of a shunt regulator circuit employing the principles of the present invention.

Referring now specifically to FIGURE 1 of the accompanying drawings, there is illustrated a series regulator circuit for use with a negative voltage supply. A transformer 1 is provided with a primary circuit 2 adapted to be connected to A.C. power line and a secondary circuit 3 having its upper end, as illustrated in FIGURE 1, connected to a grounded bus 4. The lower end of the secondary circuit 3 is connected through a half-wave rectifier or diode 6 to a junction 7, connected through a filter capacitor 8 to the grounded bus 4. The circuit thus far described provides a half-wave rectified negative power supply which is illustrated for purposes of explanation only, it being understood that a full wave bridge rectifier, voltage doubler circuit, or other conventional rectifier arrangements may be employed. Also, the filter circuit which is represented herein only by the capacitor 8 may comprise a more elaborate filter circuit, such circuits being conventional in the art.

The circuit of FIGURE 1 further comprises a series regulator tube generally designated by the reference numeral 9 which constitutes a dual triode including a first section having a cathode 11, control grid 12 and anode 13. The dual regulator also includes a second section having a cathode 14, control 16 and an anode 17. The cathodes 11 and 14 are connected through voltage dropping resistors 18 and 19 respectively to the junction 7 and the anodes 13 and 17 are connected together and to a negative output voltage bus 21. The negative voltage to be regulated appears between the buses 21 and 4 and connection may be made to output terminals 22 and 23 respectively.

An error signal detection and amplification circuit includes a voltage divider having a fixed resistor 24, a second fixed resistor 26, and a fixed resistor 27 having a variable tap 28 adapted to slide thereover. The resistors 24, 26 and 27 are connected in series between the leads 4 and 21 with the resistor 27 connected between the resistors 24 and 26. The slider 28 is connected to a grid 29 of a triode 31 having a cathode 32 and an anode 33. The cathode 32 is connected through a voltage regulator tube 34 to the negative voltage bus 21 and is further connected through a voltage regulator tube 36 and a resistor 37, connected in series, to the grounded bus 4 with the resistor 37 having one end directly connected to the grounded bus. The glow tubes 34, 36 and resistor 37 constitute a voltage divider which is adapted to establish a fixed negative potential on the cathode 32 of the tube 31 and which therefore serves as a voltage reference for the regulator system.

The anode 33 of the tube 31 is directly connected to a cathode 38 of a further triode 39 having a control grid 41 and an anode 42. The control grid 41 is connected to the junction of the glow tube 36 and the resistor 37 and therefore has a fixed potential established thereon. The anode 42 of the tube 39 is connected via a lead 43 to a positive voltage terminal of a low capacity power sup-

ply 44 having a negative terminal connected to a junction point 46. The junction point 46 is connected through a first resistor 47 to the control grid 12 of the first section of the tube 9 and is also connected through a second resistor 48 to the control grid 16 of the second section of the tube 9. The junction 46 is also connected through a load resistor 49 to the junction 7 previously described.

The tubes 31 and 39 constitute a cascode amplifier circuit, this type of circuit being employed because of the high gain which may be obtained with a relatively small number of tubes. The voltage developed at the anode 42 of the tube 39 must be such relative to the voltage of the cathode 32 to permit the tubes 31 and 39 to operate in their normal transconductance regions. The voltage on the anode 42 is developed by the power supply 44 which has its negative terminal connected to the junction point 46. It will be noted that since current through an electron tube flows from the anode to the cathode, current flows through the load resistor 49 from the left to the right as viewed in FIGURE 1. In consequence, the junction point 46 is negative relative to the junction point 7 and by suitably choosing the voltage of supply 44 and the quiescent voltages on the control grid 29 and cathode 32 and the value of the resistor 49, a suitable bias voltage may be developed on the grids 12 and 16 of the tube 9. In a typical example, if the voltage at the junction 7 is at, for instance, minus 500 volts and the lead or bus 21 is to be maintained at minus 400 volts, the voltage of the supply 44 should be approximately 550 volts in order to raise the anode 42 to a negative voltage of no less than minus 200 volts. In such a system, the cathode 32 should be operated at minus 315 volts and the grid 41 at minus 250 volts. Under no signal conditions, the grid 29 should be at a negative potential relative to the cathode 32 and should establish class A operation for the cascade amplifier circuit. The slider 28 is positioned on the resistor 27 so as to establish a predetermined voltage on the bus 21 and in the event of deviation of this voltage therefrom the voltage on the grid 29 is varied. For instance, if the voltage on the bus 21 becomes less negative relative to the grounded bus 4 than is desired, the cathode 32, being directly connected to the bus 21, is more affected by the voltage change than the grid 29 and the bias on the tube 31 is increased. Thus, triodes 31 and 39 function as a differential cascode amplifier to derive an error signal indicative of the difference between the reference potential at cathode 32 and the load voltage indicating signal supplied to grid 29. Conduction through the cascode amplifier is decreased and current flow through the load resistor 49 is decreased. This renders the grids 12 and 16 of the tube 9 more positive than previously and increases conduction through the tube 9. As a result, the voltage on the lead 21 again becomes more negative and regulation is instituted.

It will be noted that the error signal amplifier circuit is direct coupled to the regulator tube 9 and therefore the low frequency response of the system is excellent. The high frequency response of the system is determined in part by the interelectrode capacities of the various tubes and further by the shunt capacity to ground of the power supply 44. More particularly, if the power supply 44 has a high leakage capacity to ground, this capacity, appearing as a low impedance to high frequencies, materially reduces the response of the system to the high frequency components of the error signal. Therefore, the power supply 44 should have a very low shunt capacity to ground and may constitute a power supply as disclosed and claimed in the aforesaid U.S. patent. The shunt capacity to ground of the power supply disclosed in the aforesaid patent is between 15 and 20 micro-microfarads so that the high frequency response of the system is very good up to frequencies of one megacycle per second. The upper range of the response of the system may be extended but the utilization of compensation circuits described in co-pending application Ser. No. 777,037, filed

November 28, 1958, for "Wide Band Direct Coupled Amplifier" by J. H. Reaves and J. F. Walton.

Another important feature of the circuit of FIGURE 1 is that the tubes 31 and 39 constitute a constant current circuit which is substantially independent of variations of the voltage at the anode 42 over a large range of values. In consequence, the A.C. operating potential to the grid-cathode circuits of the tube 9 is substantially independent of variations in the unregulated output voltage appearing at terminal 7 and is dependent only on variations in the regulated output voltage which are applied to the grid 29 of tube 31.

It is apparent from the above description that the power supply 44 serves as an element for isolating the regulator control circuit from the very low voltages at which the regulator tube 9 must be operated. The difference in operating levels between these two circuits may be quite large and is limited only by the convenience of obtaining specific physical and electrical characteristics in a power supply connected as the source 44 in FIGURE 1 of the accompanying drawings. In practice low capacity supplies of 2500 to 3000 volts have been found to be entirely practical and such supplies may be employed in circuits of the type illustrated in FIGURE 1 where the disparity in voltages between the controlling and controlled circuits are considerably greater than those set forth above for purposes of explanation.

The important feature of the circuit of FIGURE 1 is that the series regulator tube may be connected in the negative side of the negative voltage supply and regulation obtained completely independently of any circuits employed to regulate a positive voltage which may be developed by circuits employing a common return or ground bus such as the bus 4 illustrated in FIGURE 1. As indicated above, this capability results from the utilization of the low capacity power supply 44 which, as a result of its connection between the load resistor 49 and the anode 42 of the tube 39 develops a voltage at the junction of the load resistor and the supply which is more negative than the voltage of the cathodes 11 and 14 of the tube 9; that is, develops a voltage at the junction 46 which is lower than the lowest voltage supplied by the power supply whose voltage is to be regulated.

The principles of utilization of the isolated power supply to develop the necessary negative voltage on the grid of the control tube relative to its cathode, where the cathode is operating at near the most negative point in the circuit, may also be applied to a shunt regulator circuit as illustrated in FIGURE 2 of the accompanying drawings. The unregulated negative voltage; that is, the voltage from a rectifier power supply or other source of negative potential, is connected between a bus 51 and a grounded bus 52. A resistor 53 is connected between the bus 51 and a negative voltage supply bus 54 connected to an output terminal 56, there also being an output terminal 57 connected to the grounded voltage bus 52. In order to obtain regulation of the voltage on the negative voltage bus 54 varying amounts of current are drawn through the resistor 53 and under control of a regulator connected in shunt with the terminals 56 and 57. More particularly, there are provided four tubes, all of which are generally designated by the reference numeral 58, connected in parallel and having their anodes 59 connected to the grounded voltage bus 52 and their cathodes 61 connected through current limiting resistors 62 to the negative voltage bus 54. Control grids 63 of tubes 58 are all connected to a common lead 64 connected in turn to a junction point 66 adapted to have an error signal potential applied thereto.

By appropriately regulating the error voltage applied to the junction point 66, the current flow through the tubes 58 may be controlled so that the current flowing through the resistor 53 is at all times such as to maintain a predetermined potential on the bus 54.

The resistors 62 in the cathode circuits of the tubes 58 are quite small and may be entirely eliminated. They are

employed strictly to prevent excessive currents from being drawn through the tubes 58 in the event of malfunction which currents would tend to destroy the tubes if the resistors 62 were not employed. If this safety feature is not desired then the resistors 62 may be completely eliminated. The reason for maintaining the resistor 62 at a very low value is to permit the circuit to control a large range of selected negative potentials on the bus 54 with a relatively small number of tubes. By employing small value resistors in the cathode circuit of the tubes, the maximum current through the tubes 58 is limited almost entirely by their characteristics. By appropriate selection of the tubes, the range of quiescent currents that may be established with a given number of tubes is large and consequently the range of voltages over which the output voltage may be varied is large relative to the number of tubes connected in parallel. The advantage to employing large resistors in the cathode circuit is that a proper operating grid-cathode bias may be obtained thereby. However, in accordance with the present invention, it is not necessary to employ the large resistors to obtain the requisite bias and therefore the cathode resistors may be either eliminated or held to a very small value to provide the advantages indicated above.

Proceeding with the description of the circuit for developing the control voltage to be applied to the junction point 66, there is provided a voltage divider between the buses 54 and 52 comprising a resistor 67 having one end connected to the bus 52, a resistor 68 having one end connected to the bus 54 and a resistor 69 connected between the resistor 67 and 68. A tap 71 is adapted to slide along resistor 69 to provide for adjustment of the voltage to be maintained on the lead 54. The tap 71 is connected to a grid 72 of a first section of a twin triode 73 connected as a differential amplifier. The first or left section of the tube 73 further comprises a cathode 74 connected to a cathode 76 of a second section of the tube 73, the two cathodes being connected through a large resistor 77 to the negative voltage bus 54. An anode 78 of a first section of the tube 73 is directly connected to a cathode 79 of a first section of a second twin triode 81 having an anode 82 connected to the bus 52. An anode 83 of the second section of the tube 73 is connected directly to a cathode 84 of a second section of the tube 81 having an anode 86 connected to a positive terminal of a low capacity power supply 87. The negative terminal of the supply 87 is connected to the junction point 66 which in turn is connected through a load resistor 88 to the negative voltage bus 54. In order to provide fixed operating potentials for a control grid 89 of the second section of the tube 73, and control grids 91 and 92 of the triode 81 there is provided a resistor and voltage regulator tube network. This network includes a resistor 93 having its upper end connected to the grounded bus 52 and its lower end connected through a first regulator tube 94 to the negative voltage bus 54. There is further provided three resistors 96, 97 and 98 connected in series in the order mentioned between the negative voltage bus 52 and a junction point 99. The junction point 99 is connected through a by-pass capacitor 101 to the negative voltage 54 and is also connected to the junction of the resistor 93 and a regulator tube 94. The junction 99 is connected through a resistor 102 to the control grid 89 of the tube 73 and is also connected through a second voltage regulator tube 103 to the junction of the resistors 96 and 97.

The voltage regulator tube 94 maintains the voltage at the junction point 99 at a fixed potential depending upon the voltage to be maintained on the negative voltage bus 54 and therefore maintains the control grid 89 of the second section of the twin triode 73 at a fixed potential. Similarly, the second voltage regulator tube maintains the voltage drop across resistors 97 and 98 at a fixed potential depending upon the voltage on the negative voltage bus 54 and in consequence, maintains the control

grids 91 and 92 of the tube 81 at a fixed potential, depending upon the desired negative output voltage.

The resistors 67, 68 and 69 on the one hand and the tubes 81 and 73 and resistor 77 on the other constitute two parallel voltage dividers. The relative values of the various impedances in the two voltage dividers must be such that upon a change in voltage on the negative voltage bus 54, the initial change in voltage on the cathodes 74 and 76 is greater than the initial change voltage on the grid 72. This may be accomplished by making the value of the resistor 77 small relative to the value of the resistor 68.

In operation, if it is assumed that the voltage on the bus 54 becomes more negative than the desired value, the change in voltage has more effect upon the cathode 74 than upon the grid 72 and, in effect, the grid 72 swings positive relative to the cathode. This increases current flow through the first or left hand section of the tube 73 and due to the differential effect in the amplifier decreases current flow through the right hand or second section of the tube 73. The voltage at the point 67 becomes more positive relative to the bus 54, and current flow through the tubes 58 is increased. The increase in current flow causes an increased voltage drop through the resistor 53, thereby causing the voltage bus 54 to become less negative and completes the regulating action.

The utilization of the low capacitance power supply 87, which may be of the same type as described relative to the power supply 44 of FIGURE 1, is employed to obtain a proper operating bias on the grids 63 of the tubes 58. As previously indicated, the resistors 62 may be either eliminated or if employed are of such a low impedance as not to provide a proper operating bias for the tubes. Since the voltage 54 is the most negative voltage in this portion of the system, some means must be provided for obtaining a voltage on the grid 63 negative relative to the voltage on the negative voltage bus 54. This is accomplished by the utilization of the particular connection of a low capacity power supply between the anode 86 of the tube 81 and the load resistor 88 of the differential amplifier. As a result of the fact that current flow through the resistor 88 is in an upward direction, as viewed in FIGURE 2, the junction 66 is maintained at a potential negative relative to the bus 54 whenever current is drawn through the resistor. The extent to which the junction 66 is negative relative to the cathode is determined, under no signal conditions, by the quiescent or no signal current flowing through the right hand stage of the differential amplifier and by the value of the resistor 88. These two parameters are chosen such that a proper potential is obtained at the junction point 66. These factors also determine the value of the voltage provided by the power supply 87 and if in the typical example the tubes 58 are tube types 6BL7, the tubes 81 and 73 are tube types 6922 and the load resistor 88 is 220,000 ohms then in order to produce a voltage range on the bus 54 of from minus 350 to minus 450 volts, the power supply 87 should provide a voltage of at least 250 volts D.C.

As previously indicated with respect to FIGURE 1, the degree of regulation obtainable is a function of the amplification factor provided by the control system. In consequence a differential cascode amplifier which includes the tubes 73 and 81 is employed to provide maximum gain with a minimum number of tubes, it being found that for most purposes, the gain produced by these tubes is sufficient to obtain good regulation of the circuit; that is regulation within plus or minus one-half of one percent of the selected voltage. Increased regulation may be obtained by simply cascading stages of amplification and/or employing more tubes in parallel with the tubes 58.

While I have described and illustrated several embodiments of my invention, it will be clear that variations of the details of construction which are specifically illus-

trated and described may be resorted to without departing from the true spirit and scope of the invention as defined in the appended claims.

What I claim is:

- 5 1. A voltage regulator circuit for a D.C. load responsive to a D.C. source comprising an electron tube responsive to said source, said tube having at least a cathode, an anode and a control grid, means connecting said electron tube to vary the potential across said load in response to variations in current through said tube, a control circuit connected to said load for developing a signal voltage indicative of the voltage across said load, said control circuit having an output stage including a second electron tube connected to said control circuit, said second electron tube comprising a second cathode and a second anode, an anode voltage supply, a load resistor connected to the grid of said first electron tube, means connecting said anode supply between one terminal of said load resistor and the grid of said first electron tube and said anode of said second electron tube, the other terminal of said load resistor being connected to a supply terminal, and means connecting said control grid to said load resistor.
- 10 2. A series voltage regulator circuit for a D.C. load responsive to an unregulated D.C. supply comprising a pair of leads connected across said load and having a voltage to be regulated developed thereacross, one terminal of said supply and one of said leads having a common connection, an electron tube having a cathode, an anode and a control grid, said cathode being connected to the other terminal of said supply, said other terminal and the other of said leads being at negative potential relative to said common connection, said anode being connected to said other lead, a control circuit for developing an error voltage proportional to variations in the voltage across said load from a predetermined value, a source of potential, and means for connecting said error voltage to said control grid through said source of potential, said source of potential being such as to establish a proper operating bias on said control grid relative to said cathode of said electron tube.
- 15 3. The combination according to claim 2 wherein said control circuit comprises plural stages and has a final stage including a second electron tube, said second electron tube having a second cathode and a second anode, means connecting said second cathode to said other lead, a load resistor and means connecting said anode of said second tube through said source of potential to said load resistor and means connecting said load resistor between said control grid and said cathode of said first-mentioned electron tube.
- 20 4. The combination according to claim 3 wherein said control circuit includes a differential amplifier and wherein in said final stage of said control circuit constitutes one section of said differential amplifier.
- 25 5. The combination according to claim 4 wherein said differential amplifier is a cascode amplifier.
- 30 6. A shunt voltage regulator for a D.C. load responsive to a D.C. source comprising a pair of leads having an unregulated voltage developed thereacross, an output terminal connected to said load, a resistor connected between one of said leads having the more negative voltage developed thereon and said output terminal, an electron tube having an anode, a cathode and a control grid, said cathode being connected to said output terminal and said anode being connected to the lead of said pair of leads having the more positive voltage developed thereon, a control circuit including a cascode differential amplifier for developing an error voltage proportional to the deviation of the voltage on said output terminal from a predetermined value, said control circuit being responsive to a signal proportional to the D.C. voltage across said load, and including a second electron tube, said second electron tube comprising a second cathode and a

second anode, a source of potential connected to said second anode, and means for applying said error voltage to said control grid through said source of potential, said source having a voltage and being poled such that said control grid has an operating bias developed thereon relative to said cathode.

7. A shunt voltage regulator for a D.C. load responsive to a D.C. source comprising a pair of leads having an unregulated voltage developed thereacross, an output terminal, a resistor connected between the lead having the more negative voltage developed thereon and said output terminal, an electron tube having an anode, a cathode and a control grid, said cathode being connected to said output terminal and said anode being connected to the lead of said pair of leads having the more positive voltage developed thereon, a control circuit connected to said load for developing a signal voltage proportional to the deviation of the voltage on said output terminal from a predetermined value, said control circuit being responsive to a signal proportional to the D.C. voltage across said load, said control circuit having an output stage including a second electron tube, said second tube having an anode, a load impedance, a source of potential connected between and coupling said signal voltage between said anode of said second tube and said load impedance, and means connecting said control grid to said load impedance, said source having a voltage and being poled such as to provide an operating control grid bias for said first-mentioned tube and to provide the anode potential for said second tube.

8. The combination according to claim 7 wherein said control circuit includes a differential amplifier and wherein said output stage comprises one section of said differential amplifier.

9. The combination according to claim 8 wherein said differential amplifier in a cascode amplifier.

10. A circuit for regulating the D.C. potential across a load despite variations in a first D.C. source coupled to the load and in the load impedance comprising means for establishing a D.C. voltage reference level, means responsive to the voltage across said load and said voltage reference level for deriving an error signal indicative of the difference between said load and reference voltages, said last-named means including a first discharge device having a first emitter of charged carriers, a first collector for said carriers and a first control electrode for controlling the flow of charged particles between said first emitter and first collector, said first control electrode being responsive to a signal proportional to the D.C. voltage across said load, a variable regulating impedance in series between said load and said first source, said impedance including a second electron discharge device having a second emitter of charged particles, a second collector for said particles and a second control electrode for controlling the flow of charged particles between said second emitter and collector, a second D.C. voltage source connected between said first collector and second control electrode, the impedance of said second voltage source being such that said error signal is coupled between said first collector and second control electrode, said second voltage source being connected in series with said first emitter and first collector for energizing the emitter collector path of said first discharge device, means for connecting the emitter collector path of said second discharge device to be energized by said first D.C. source, the amplitude of said second voltage source being sufficient to bias said first collector electrode so that it collects said charged particles and to bias said second control electrode so that it is biased at a more negative voltage than the high voltage terminal of said first D.C. source.

11. The circuit of claim 10 wherein said second discharge device is in series between said first D.C. source and said load.

12. The circuit of claim 10 wherein said second discharge device is in shunt between said first D.C. source and said load.

13. The circuit of claim 10 further including a load impedance for said error voltage, said load impedance being connected in a D.C. circuit between said second emitter and second control electrode.

14. A circuit for regulating the D.C. potential across a load despite variations in a first D.C. source coupled to the load and in the load impedance comprising means for deriving an error signal indicative of the voltage across said load, said last-named means including a first discharge device having a first emitter of charged carriers, a first collector for said carriers and a first control electrode for controlling the flow of charged particles between said first emitter and first collector, a D.C. path between one side of said load and said first emitter, said first control electrode being responsive to a signal proportional to the D.C. voltage across said load, a variable regulating impedance in series circuit between said load and said second source, said impedance including a second electron discharge device having a second emitter of charged particles, a second collector for said particles and a second control electrode for controlling the flow of charged particles between said second emitter and collector, a second D.C. voltage source connected between said first collector and second control electrode, the impedance of said second voltage source being such that said error signal is coupled between said first collector and second control electrode, said second voltage source being connected in series circuit with said first emitter and first collector for energizing the emitter collector path of said first discharge device, means for connecting the emitter collector path of said second discharge device to be energized by the first D.C. source, the amplitude of said second voltage source being sufficient to bias said first collector electrode so that it collects said charged particles and to bias said second control electrode so that it is biased at a more negative voltage than the high voltage terminal of the first D.C. source.

15. The circuit of claim 14 further including a load impedance for said error voltage, said load impedance being connected in a D.C. circuit, between said second emitter and second control electrode.

16. A circuit for regulating the D.C. potential across a load despite variations in a first D.C. source coupled to the load and in the load impedance comprising means for deriving an error signal indicative of the voltage across said load, said last-named means including a first discharge device having a first emitter of charged carriers, a first collector for said carriers and a first control electrode for controlling the flow of charged particles between said first emitter and first collector, a D.C. path between one side of said load and said first emitter, said first control electrode being responsive to a signal proportional to the D.C. voltage across said load, a pair of leads connected to said first D.C. source and coupled to the load, a resistor connected between the one of said leads having the more negative voltage developed thereon and the output terminal a variable regulating impedance in series between said load and said first source, said impedance including a second electron discharge device having a second emitter of charged particles, a second collector for said particles and a second control electrode for controlling the flow of charged particles between said second emitter and collector, a second D.C. voltage source connected between said first collector and second control electrode, the impedance of said second D.C. voltage source being such that said error signal is coupled between said first collector and second control electrode, said second D.C. voltage source being connected in series circuit with said first emitter and first collector for energizing the emitter collector path of said first discharge device, means for connecting the emitter collector path of said second discharge device to be energized by said first D.C. source, the amplitude of said second voltage source being sufficient to bias said first collector electrode so that it collects said charged particles and to bias said second control electrode so that it is biased at a more negative voltage than the high voltage terminal of said first D.C. source.

11

of said second discharge device to be energized by said first D.C. source.
